(57) **CLAIM**

We claim the ornamental design for a drying rack, as shown and described.

DESCRIPTION

FIG. 1 is an isometric top, front view of a drying rack; FIG. 2 is an isometric bottom, rear view thereof; FIG. 3 is a top view thereof; FIG. 4 is a bottom view thereof; FIG. 5 is a right side view thereof; FIG. 6 is a left side view thereof; FIG. 7 is a front view thereof; FIG. 8 is a rear view thereof; FIG. 9 is a sectioned left elevation view thereof, the section being taken in a direction of section line 9-9 of FIG. 2; and, FIG. 10 is a sectioned front elevation view thereof, the section being taken in a direction of section line 10-10 of FIG. 2.

The evenly spaced broken lines in the drawings depict portions of the embodiments of the drying rack forming no part of the claim.

The closely parallel and unevenly spaced broken lines denoting unnumbered sections through the body of the drying rack indicate the option for varied expansions therewith.
